UNITED STATES PATENT OFFICE.

FREDERICK H. JOHNSON, OF EAST GREENWICH, RHODE ISLAND.

DESIGN FOR A BUTTON, BADGE, EMBLEM, PIN, OR ARTICLE OF SIMILAR NATURE.

61,306.

Specification for Design.

Patented Aug. 1, 1922.

Application filed January 4, 1922. Serial No. 32. Term of patent 7 years.

To all whom it may concern:

Be it known that I, FREDERICK H. JOHNSON, a citizen of the United States, residing at East Greenwich, in the county of Kent and State of Rhode Island, have invented a certain new, original, and ornamental Design for a Button, Badge, Emblem, Pin, or Article of Similar Nature, of which the following is a specification.

In the accompanying drawing which forms a part of this specification,

The figure is a front elevation of an emblem embodying my new design.

One of the two lower triangles comprises parallel strips of violet, purple, blue, green, yellow, orange, and red. The other lower triangle comprises strips of blue and red. The uppermost triangle is of the color of one of the strips of the first mentioned triangle, in this instance blue.

I claim:—

The ornamental design for a button, badge, emblem, pin, or article of similar nature, as shown.

FREDERICK H. JOHNSON.
